UNITED STATES PATENT OFFICE.

CHARLES F. KULP, OF WELLSTON, MISSOURI.

STOVE.

1,380,396.

Specification of Letters Patent. Patented June 7, 1921.

Application filed January 2, 1918. Serial No. 209,913.

To all whom it may concern:

Be it known that I, CHARLES F. KULP, a citizen of the United States, residing at Wellston, in the county of St. Louis and 5 State of Missouri, have invented certain new and useful Improvements in Stoves, of which the following is a specification.

My invention has for its object to improve the general construction of stoves using oil 10 as a fuel in connection with a tubular wick and central draft burner for producing heat for cooking purposes, whereby the efficiency and usefulness are increased, smoking prevented, and a strong, steady blue-white 15 flame produced.

Another object of my invention is to provide an oil container or lamp body having a plurality of air inlet openings formed in the wall thereof, above the oil level of the 20 oil chamber, to prevent the oil chamber from getting hot and generating gas which will cause the flame to rise and smoke.

A still further object of my invention is to provide means adapted to act as a stove 25 top and further produce the necessary draft through the burner and around the flame.

For a full understanding of the merits and advantages of the invention, reference is to be had to the accompanying drawings 30 and the following specification.

Referring to the accompanying drawings wherein like characters denote similar parts throughout the several views:

Figure 1, is a side elevation of my im- 35 proved oil stove constructed and assembled in accordance with my invention.

Fig. 2, is a plan view of the stove.

Fig. 3, is a detail of a part of the stove, partly in section and partly in side eleva- 40 tion, embodying the essential features of the invention.

Fig. 4, is a detail showing a part of the stove-top and draft creating means.

In carrying out the aim of my present in- 45 vention, I employ a suitable tubular-wick oil stove of the heating type and consisting of a support or housing 1, within which is carried an oil container 2 having the central draft burner 3, the wick 4, and flame 50 spreader 5. The aforesaid parts may be of any size, pattern, or construction accord- ing to the design of the heater, as will be readily understood hereinafter.

The wall of the oil container 2 is provided 55 with a plurality of air inlet openings or pas- sages 6, above the oil level of the container.

This arrangement or construction of oil container permits the free circulation of air in the oil chamber thereof and around the tubular lamp wick 4, thus preventing the oil 60 container from getting hot and generating gas within the container. By eliminating the generation of gas within the oil container 2 the flame is easily regulated to produce a steady blue-white flame without 65 smoke and one which will not have the tendency to rise and smoke as most wick burning oil stoves do.

The means for feeding oil to the oil container 2 consists of a suitable pipe 7 sup- 70 ported by the housing 1. One end of the pipe 7 extends into the oil container 2 and the opposite end thereof is provided with a suitable funnel shaped member 8. An oil supply tank 9 is supported by means of a 75 bracket 10, above the funnel shaped mem- ber 8. An oil outlet pipe 11 is fixed to the bottom of the tank 9 and provided with a suitable valve 12 for controlling the flow of oil from the tank 9 into the funnel shaped 80 member 8. One can readily ascertain the amount of oil in the oil container 2 by ob- serving the level of the oil in the funnel shaped member 8, as is manifest.

The housing 1 is provided with suitable 85 supporting legs and a hinged cover 13 hav- ing the collar 14 encircling the opening 13 and surrounding the flame spreader 5 of the burner 3, as clearly shown in Fig. 3.

A hollow pan-like member acting as a 90 stove top is employed consisting of the bot- tom 15, the top 16 and the side walls 17 forming a shallow horizontally disposed draft chamber 18 therein. The bottom 15 of the pan-like member is provided with a 95 circular collar 19 and adapted to fit over the collar 14, of the cover 13, to positively position the pan-like member upon the housing 1. The bottom 15 is provided with a flame opening 20 concentric with the col- 100 lar 19 and with the flame-spreader.

The top 16 is provided with a utensil re- ceiving opening 21 which opening is con- 105 centrically disposed above the flame open- ing 20. Cover and utensil stops 22 are fixed to the top 16, as clearly shown in Figs. 2 and 3.

A plurality of air inlet openings 23 are formed in the bottom 15 concentrically with the flame opening 20 to admit cool air 110 around the flame, as is manifest. The open- ings are preferably arranged in the form of

a horse-shoe around the opening 20, as clearly shown in Fig. 4.

The top 16 of the pan-like member is provided with an opening 24 and a surrounding 5 collar 25. A draft pipe 26 of any suitable height is adapted to fit over the collar 25 and be supported thereby. This pipe 26 is but a short pipe and need not be connected with a chimney flue. When desired to be connected with a chimney flue, it is not directly connected therewith but the pipe 26 is adapted to only enter an inverted funnel at the end of the pipe connected with the flue so that too much draft will not be produced 10 through burner and pan like member. The pan-like member, it will be understood acts in the same capacity as a cooking stove top of the coal burning type and may be construed as a stove top throughout the specification and claims.

A suitable base 27 is employed upon which the housing is positioned. Brackets or standards 28 fixed to the base 27 help support the panlike stove top, as clearly shown 25 in Fig. 1.

From the foregoing description, it will be readily seen that I have constructed an oil stove for cooking and heating purposes which is simple in construction, durable and 30 highly efficient for the purposes intended.

The many advantages of a stove of this character will readily suggest themselves to those skilled in the art to which it appertains.

35 The exact construction shown is not essential to the invention and the improvement is susceptible of various minor changes in the form, proportion, and in the various details of construction without departing from the 40 principle or sacrificing any of the advantages thereof, hence I reserve the right to make any such changes or modifications as may fall within the scope of the appended claims when fairly construed.

45 What I claim is:

1. In combination, an oil stove having the fuel container provided with a plurality of air inlet passages arranged just above the fuel level, a collar arranged concentric with 50 the burner of the stove, a utensil supporting

housing having both ends closed and provided in its top plate with a utensil opening over the burner of the stove and provided with a flue opening at the extreme end of the housing, a collar depending from one end of the housing for telescopic connection with the collar of the stove for supporting one end of the housing upon the stove, the bottom plate of said housing being provided with a multiplicity of concentrically arranged draft openings adjacent the upper end of the depending collar of the housing partly surrounding the collar and disposed in a substantial plane with the top of the burner within the collar, a support for the opposite end of the housing and a draft pipe 55 extending upwardly from the flue opening of the housing.

2. In combination, an oil stove having the fuel container provided with a plurality of air inlet passages arranged just above the fuel level, a collar arranged concentric with the burner of the stove, a utensil supporting housing having both ends closed and provided in its top plate with a utensil opening over the burner of the stove and provided with a flue opening at the opposite extreme end of the housing, a collar depending from one end of the housing for telescopic connection with the collar of the stove 60 for supporting one end of the housing upon the stove, the bottom plate of said housing being provided with a multiplicity of concentrically arranged draft openings adjacent the upper end of the depending collar of the housing partly surrounding the collar and disposed in a substantial plane with the top of the burner within the collar, a support for the opposite end of the housing, a draft pipe 65 extending upwardly from the flue opening of the housing, a liquid fuel pipe extending into the fuel container below the air inlet passages, a fuel reservoir fixed to the outer end of the fuel pipe and means for supplying said reservoir with liquid fuel 70 from where it is conducted to the fuel container of the stove.

In testimony whereof, I have hereunto signed my name to the specification.

CHARLES F. KULP.
